UNITED STATES PATENT OFFICE.

THOMAS ERNEST RAYMOND PHILLIPS, OF LIVERPOOL, ENGLAND.

AERIAL VESSEL.

1,043,538.

Specification of Letters Patent.

Patented Nov. 5, 1912.

Application filed November 12, 1910. Serial No. 592,057.

To all whom it may concern

Be it known that I, THOMAS ERNEST RAYMOND PHILLIPS, a subject of the King of England, residing at 15 Nicander road, Sefton Park, Liverpool, in the county of Lancaster, England, have invented Improvements in Aerial Vessels, of which the following is a specification.

This invention has reference to the controlling of aerial and other vessels, and equivalently operated apparatus, by wave transmitted electricity, but it will be primarily described as applied to, or used in connection with, the controlling of the movement or action of aerial vessels whether of the lighter than air type, or heavier than air type, in connection with which it is very applicable; it being understood at the same time that it may be also applied to apparatus or machinery which can be equivalently controlled and operated from a distance by wave transmitted electricity.

In the following description, the improvements under this invention are comprised, such description being made in connection with the controlling of an aerial vessel or apparatus.

In connection with the aerial vessel, there are employed a motor and propellers which are mounted on a loosely supported frame capable of swinging in or near the horizontal plane, and also slightly tilting or moving in relation to the vertical plane from its point of support; and the engines or electric motors are carried on this frame, and are arranged, say, one on either side of the vertical plane of the vessel, and adapted to be put in action separately or together. When actuated separately in one direction, this frame is caused to swing thereby about its support, and so produce an oblique propelling effect, tending to turn the vessel around; while when this motor is put out of action, and the other put in motion, the opposite propelling and turning effect is obtained, while in some cases, if desired, it may be devised so that one will be revolved in one direction, and the other in the other direction. Further, in another part of the apparatus, that is, in the frame of the vessel, there may be provided an electric motor, or an electrically controlled motor, operating a propeller horizontally, which, when worked in one or other direction, tends either to lift the vessel or depress it, so that it can rise or fall as desired. These motors

or their controlling mechanism will be operated by electrical accumulators or batteries, held or carried in a suitable part of the vessel. The actions of these motors are governed by wave actuated electrical appliances on the vessel. These will comprise receiver bars or the like connected with terminals, which have in connection with them a coherer which is decohered by a suitable electro-magnet. In connection with the circuit and one of the coherer terminals, there will be a battery and a relay, and these are so arranged that when a wave is transmitted from the transmitting instrument, such as is produced by a suitable oscillator, the relay through the coherer will be actuated, and this will close a local circuit connected with an electro-magnet which operates a current controller for governing the various circuits of the motors and other appliances on the vessel. This circuit opening and closing device will have a plurality of sets of tappets or projecting contacts which operate in connection with other contacts constituting the terminals of the circuits of the different motors, and these several sets of contacts will be mounted on a barrel circularly and longitudinally, the terminals referred to being arranged along say either side of the barrel. Then if this barrel be rotated from one position to another, it will be put in and out certain circuits; the various pins or contacts on the barrel being electrically connected up, and so arranged, that this can take place, and that the currents can be transmitted in one or other direction, so as to drive the motors in one direction or the other, and to put out certain of the motors, and put in action another or others, or other appliances. The actuating of this cylinder may be effected by a lever actuated by the electro-magnet referred to, which is energized by the relay local circuit when the coherer is in action; and this magnet, after thus actuating the lever and the barrel or cylinder, will move a part into contact with the part connected with a coherer or decohering electro-magnet, so that when the circuit of this decohering magnet is thus closed, the electro-magnet actuates a hammer which strikes the coherer, so that the primary circuit is then opened. Thus by the actuation of the electrical wave transmitter, the rotary controller of the various circuits connected with the motors or other electro-magnetic devices

may be actuated, and any of these motors and devices operated in any manner required. The aerial vessel thus may be propelled directly forward or backward, or brought down, or lifted up, or maneuvered in any desired way. Furthermore, articles may be dropped from the vessel by actuating a releasing electro-magnet, and other devices (not shown). In connection with the motors and apparatus on the vessel or machine, there are electric lamps or signals, which are actuated by the electric wave through circuits, which are controlled by contacts on the cylinder or barrel referred to; and these are so arranged that it will be indicated to the operator whether the apparatus has properly received the electrical wave current or action, or not, and the whole actions of the different parts of the apparatus can be thus made known to the operator.

An example of this invention applied to an aerial machine, such as a dirigible balloon, is illustrated in the accompanying drawings, in which,—

Figure 1 is an illustration of part of the complete machine with the electrical mechanism shown more or less diagrammatically, Fig. 2 is an end view of the frame of the machine, Fig. 3 is a view, partly in section, and to an enlarged scale, showing the selector switch for the various electrical mechanisms, and a part of the said frame; while Fig. 4 is a side view of Fig. 3. Fig. 5 is a diagram illustrating the electrical connections between the electrical mechanisms hereinafter referred to.

In these drawings, 7 is an air or gas containing envelop, and 8 is a frame which is connected to the said envelop by suitable attachments 9. The frame 8 is preferably composed of three longitudinal members arranged in triangular form in cross section, and connected at each end, and terminating with pointed portions as illustrated in Fig. 1; and to this frame 8 are attached, propellers 10 for effecting the raising and lowering of the machine; propellers 11 for propelling and steering the machine; lamps 12; a tray 13; and an electrical selector mechanism 14, which is electrically connected with the other said mechanisms; while a suitable source of electricity, such as an electrical accumulator 15, is also mounted on the frame, and is connected by leads to the said mechanisms.

The propellers 11, which serve for propelling the machine forwardly or rearwardly, and for steering the same, and the motors 11^a for driving the propellers, are mounted on a loosely suspended frame 16, which is free to turn about a vertical axis relatively to the said frame 8; such turning movement being limited or controlled by means of flexible connections, such as wires,

cords, or their equivalents 17 arranged between the loosely suspended frame 16 and the frame 8.

The motors of the several propellers are connected with the selector switch mechanism 14, and the accumulator 15; while the lamps are preferably so arranged in the circuits of the motor and the controlling mechanism that one or more of these are lighted up when one or more of the electrical circuits are completed, so that it can be ascertained at a glance if the mechanisms of the several parts and the different circuits are acting efficiently.

Referring to the selector switch mechanism (see Figs. 3 and 4), this comprises a rotary drum or cylinder 19, which is rotated step by step by an electrically actuated pawl mechanism 20; and is provided with a number of contacts 21 which are adapted to engage with spring contact arms 22 connected with the several motors of the propellers, and the other electrically controlled and actuated parts. The contacts 21 are disposed in predetermined peripheral and longitudinal positions on the drum or cylinder 19, while the spring contact arms are connected through suitable terminals 22^a with the parts which are under the control of the contact arms.

The drum or cylinder 19 is suitably supported in brackets 23, and has attached to its spindle a ratchet wheel 24, which is engaged by means of the pawl or its equivalent 20 mounted on or connected with a pivotally mounted lever 26, which is actuated by a magnet 27 and a spring 28, the latter of which serves to return the lever 26 to its normal position; while the magnet serves to vibrate the same and effect the rotation of the said drum or cylinder 19.

The electro-magnet 27 which actuates the levers 26 for rotating the drum 19, is energized by the source of electricity 15 when the circuit of the same is completed; and the completion of this circuit is effected through the medium of a relay switch 28 (see Fig. 5), which is controlled by means of a coherer 29, and an electric battery 30. The relay 28, coherer 29, and battery 30, are all arranged in one circuit; and the relay is adapted to close a switch 31, whereby the main power circuit is completed, and the magnet 27 energized, by the battery 15. The coherer circuit is completed by means of electric current waves, transmitted from a distance by any suitable and known form of electric or Hertzian wave transmitting apparatus; and such wave currents are collected by the arms or antennae 32, which consist of metal rods 125 or arms preferably extending laterally of the machine. These rods or arms are adapted to receive or collect the wave actions transmitted from the arms of the said transmission device, and the collection of these 130

wave actions causes the metallic particles contained in the coherer, to so arrange themselves as to complete the coherer circuit, and effect the actuation of the relay, as above stated. The coherer circuit is broken by disturbing the particles within the coherer; and such disturbing of these particles is effected by means of the hammer 33, which is controlled by the decohering magnet 34, connected with the main local battery 15; and this is brought into circuit when the magnet 27 (controlling the lever which actuates the drum 19) is energized through the contacts 35. Fig. 5 also illustrates the various electrical circuits between the motors of the different propellers, the electrical selector switch, and the main local source of electricity 15. In this figure 10^a designates the motors of the raising and lowering propellers; while 11^a designates the motors of the propelling and steering propellers; and these several motors are connected with the before mentioned contact arms 22 of the electrical selector switch; and as the drum 19 is rotated by the lever 26, pawl 20, and ratchet wheel 24, the pins 21 of the drum make contact with the contact arms 22, and thus complete, in a predetermined order, the circuits of the various motors.

If desired, a number of lamps 12 may be employed in connection with the circuits, and according to the manner in which these light up, so will it be ascertained what circuits are completed, and what motors and propellers are in use. If reference is made to Fig. 5 it will be seen that the manner of controlling these several motors is diagrammatically illustrated. In the arrangement shown, the drum 19 is divided up into four parts, the parts *a* and *b* being reserved for controlling the motors on the loosely suspended frame 16, which serves the purpose of propelling and steering the machine; *c* for controlling the motors which serve to raise and lower the machine; and *d* for lighting up the several signal lamps.

The devices for transmitting the electrical or Hertzian wave currents to the machine may be of any known forms; although that type of apparatus provided with long thin wave transmitting rods or arms is preferred.

In use, the electrical wave actions are transmitted from the transmitting apparatus to the coherer on the aerial machine; and on each wave transmission, the coherer is energized and its circuit completed; whereupon the relay switch is actuated and the main local circuit is closed, and the magnet, which serves to actuate the drum moving lever, is energized and effects a predetermined and partial rotation of the selector drum; while following the energizing of the magnet, which moves the actuating lever of the selector drum, the decohering magnet is energized, and the hammer disturbs the par-

ticles in the coherer and breaks its circuit. The partial rotation causes certain of the contact pins to make contact with certain of the contact arms for completing their circuits. If after one wave current transmission, it is desired to alter the course of the machine or raise or lower it, other wave transmissions are made for rotating the selector drum to the position necessary to effect this purpose.

Referring to the various circuits illustrated in Fig. 5, those connected with the part *a* of the rotary switch 19, control one of the propelling motors 11^a, the leads through the field of the motor passing from the positive side of the local battery 15 to the field, and thence to the middle contact shown on the lower portion of the part *a*. This middle contact is connected to a contact on the opposite side of the drum 19, and passes thence to the negative side of the battery, thus the circuit of such propelling motor 11^a, is completed. In like manner it will be seen that the other motors 10^a and 11^a are connected up according to the position of the rotary drum 19. The rotary drum is rotated by means of the magnet 27 as previously explained, the circuit of this magnet 27 being completed when the relay switch is actuated by the completion of the coherer circuit. This coherer circuit is shown in Fig. 5, and includes the local battery 30 of small power, and the relay switch 28 and the coherer 29. When the coherer circuit is closed by a Hertzian wave current received by the arms 32, the relay switch 28 is actuated and closes the switch 31; the closing of this switch 31 effects the operation of the electro-magnet 27, which controls the operation of the drum 19. The circuit closed by the switch 31 comprises the leads from such switch 31 to the coils of the magnet 27, and the leads pass thence to the battery 15, the opposite end of this battery being connected direct to the switch 31 by the leads as shown. When the coils of the magnet 27 are energized, the switch 35 is closed, and thus this switch 35 is closed at the same time as the switch 31, and the switch 35 enables the decohering magnet to be brought into circuit also, the circuit of this decohering magnet 34 extending from the coils of such magnet to the negative side of the battery 15 and from the positive side of such battery to the coil of the magnet 27, through the switch 35 to the make and break contact of the magnet 34.

When it is desired to alter the course of the machine, that is, cause it to move to the left or right, the motors on these sides are brought into operation, and those on the opposite sides reversed if desired. This has the effect to move the loosely suspended frame relatively to the frame 8 of the machine and to pull it by means of the connec-

tions 17 in a direction different to that in which the machine is traveling. By this loosely suspended frame the machine can be caused to turn in a smaller space than if the frame was fixed; although it will be obvious that the employment of a loosely suspended frame is not essential but is advantageous.

The tray device 13 is controlled by an electromagnet 36, and serves to illustrate a means whereby articles can be carried, and may be dropped when the machine is at a height the dropping being under the control of a person stationed on the ground or at any other point at a distance from the machine.

Although only one form of means is described above for carrying the invention into effect, it will be obvious that these means can be considerably varied without departing from the nature of the invention, which consists in providing a machine with power driven mechanism for propelling—forwardly or rearwardly—steering, and, raising and lowering a machine or vessel, the power mechanism of which is under the control of a coherer, and an electrical selector switch, so arranged in connection with one, or more circuits and suitable local sources

of electricity, as to be brought into and out of operation by means of electrical or Hertzian wave currents transmitted thereto from a distance.

What is claimed is:—

In an aerial vessel, a main frame, a supplementary frame pivotally and loosely connected with the main frame and hanging pendantly therefrom, the frames being so connected that the supplementary frame remains in a vertical position irrespective of the inclination of the main frame with relation to a horizontal in any direction, the supplementary frame being arranged to turn upon an axis which passes through the vertical plane of the median longitudinal dimension of the main frame, propellers carried by the supplementary frame and located at equal distances from the vertical plane, which passes through the median longitudinal dimension of the main frame, and means for operating the propellers.

In testimony whereof I affix my signature in the presence of two witnesses.

THOMAS ERNEST RAYMOND PHILLIPS.
